GEORGE FARGHER HIGHT AND THOMAS WILLIAM BROWN, OF AUCKLAND, NEW ZEALAND.

DETACHABLE BUTTON FOR USE ON WEARING APPAREL.

Application filed August 27, 1925, Serial No. 52,862, and in New Zealand September 12, 1924.

This invention relates to buttons used for fastening or securing wearing apparel and the like in position, and has for its object the provision of an improved detachable 5 button for the aforesaid purpose, capable of being quickly and easily secured in position on, or removed from a garment as required.

According to the invention, a button is 10 secured to one side of a bar adapted to be positioned against the fabric of a garment, at that point or position on the latter where it is desired to secure said button.

This bar is provided with teeth and is 15 placed so that one of its ends projects beyond the edge of the fabric while the teeth are passed through the fabric at a short distance from the edge of the latter.

The projecting end of the bar is formed 20 to provide a guide through which a wedge shaped member is slidable, said wedge shaped member, on being forced inwards through the guide, being adapted to pass on the opposite side of the fabric to that side against 25 which the button carrying bar has been positioned.

This slideable member, on being forced inwards through its guide, contacts with the 30 points of the teeth passed through the fabric from the button carrying bar, and when wedged firmly in its guide causes the device to be clamped to the fabric and prevents the withdrawal of said teeth from the latter, the device being released or detached from 35 the garment by sliding the wedge shaped member outwards through its guide until the button carrying bar can be operated to withdraw its teeth from the fabric.

The invention will be more particularly 40 described with reference to the accompanying drawing, wherein:—

Figure 1 is a perspective view of the button secured in position on a garment or the like, and

Figure 2 is a perspective view of the device positioned on a garment but viewed from the opposite side to that shown in Figure 1.

Figure 3 is a part sectional elevation of 50 the device positioned on a garment or the like, but with the wedge shaped member withdrawn to free the points of the teeth on the button carrying bar while,

Figure 4 is a similar view to Figure 3 55 but showing the wedge shaped member

forced inwards through its guide to lock or clamp the device on the garment.

A button 1 of any desired shape, size and design or material is riveted or otherwise secured to one side of a flat bar 2 which 60 is adapted to be positioned against the outer side of the fabric 3 of a garment or the like at that point or position on the latter, where it is desired to secure said button.

The bar 2 is positioned so that its end 65 2^a projects slightly beyond the edge of the fabric 3, while its other or inner end 2^b is bent and serrated to provide a number of tooth shaped projections adapted to be entered in and passed through the fabric 3 at 70 a short distance from the edge of the latter.

The outer or projecting end 2^a of the button carrying bar 2 is formed to provide a guide 4 through which a member 5 is slideable lengthwise. This member 5 is wedge 75 shaped at its outer end, that is, said member 5 decreases in thickness, but not in width, from its outer end towards its inner end, the latter being adapted to be passed on the inner side of the fabric 3, on the opposite 80 side of the latter to that side on which the button carrying bar 2 is positioned.

To secure the button 1 in position on the garment, the member 5 is forced through its guide 4 in an inward direction so that its 85 inner end contacts against the points of the teeth formed on the button carrying bar 2, which teeth have been passed through the fabric 3. As the inner end of the member 5 comes into contact with the points of the 90 teeth, its wedge shaped outer end enters the guide 4 with the result that the said member 5 is securely held in position against the teeth on the button carrying bar 2 by the engagement or wedging of its outer end in 95 the guide 4, and the fabric 3 is clamped between said member 5 and said bar 2.

The button 1 is thereby firmly held on the garment by reason of the fact that so long as the member 5 remains in its innermost 100 position it is clamped against the points of the teeth on the button carrying bar 2 and said teeth cannot be withdrawn from the fabric 3 until the member 5 is moved outwards through its guide 4 away from said 105 teeth.

The inner end of the member 5 is extended in width, as at 6 so that on the said member being moved through its guide 4 to its outermost or disengaged position, as shown in 110

Figure 3 of the accompanying drawing, such portion 6 will be unable to pass through the guide 4, and the member 5 and button carrying bar 2 will therefore, at all times, be held together to form a single unit.

Additional teeth can, if desired, be formed on the button carrying bar 2 midway of its length as indicated at 7 in order to provide for a more distributed grip of the device on the fabric 3 of the garment.

Having thus described our invention, we declare that what we claim and desire to obtain by Letters Patent of the United States of America, is:—

15. 1. A device for the purpose specified, comprising a button secured to a bar adapted to be positioned against one side only of the fabric of a garment or the like; teeth formed on said button carrying bar, and a guide at one end thereof; a wedge shaped member 20 slideable through said guide on the opposite side of the fabric to the button carrying bar so as to clamp the fabric and retain the teeth therein.
20. 2. A device for the purpose specified, according to claim 1, wherein the button carrying bar is bent and serrated at its inner end to provide teeth adapted to be passed through the fabric, and wherein the outer end of the 25 said button carrying bar is extended beyond

the edge of said fabric and is formed to provide a guide through which a wedge shaped member is slideable on the opposite side of the fabric to that side of the latter against which the button carrying bar is 35 placed.

3. A device for the purpose specified, according to claim 1, wherein the wedge shaped member decreases in thickness from its outer end towards its inner end, and is adapted 40 on being forced inwards through the guide on the button carrying bar, to press its inner end against the points of the teeth on the latter, passed through the fabric, to prevent the withdrawal of said teeth from the 45 fabric.

4. A device for the purpose specified, according to claim 1, wherein the inner end of the wedge shaped member is increased in width, in order to prevent the complete withdrawal of the said member through the guide on the button carrying bar, on said member being moved through the latter to its outermost or disengaged position.

Signed at Auckland, in the Provincial District of Auckland, in the Dominion of New Zealand, this 24th day of July, A. D. 1925.

GEORGE FARGHER HIGHT.
THOMAS WILLIAM BROWN.
